ELECTROMAGNETIC WAVE CONTROLLING
APPARATUS

Thomas Joseph Keary, Brockton, Mass., assignor,
by mesne assignments, to the United States of
America as represented by the Secretary of the
Navy

Application September 18, 1945, Serial No. 617,141

10 Claims. (Cl. 250—33.65)

1

This invention relates generally to directional micro-wave antennas, and in particular to an antenna having a paraboloidal reflector together with an apparatus that may be considered to produce the same result effectively as an electrically off-focus feed source periodically variable in position so as to produce a rapid narrow swing scanning by the reflected radiation beam.

It had been previously observed that when a paraboloidal reflector is illuminated by a dipole with a reflecting disk near its focus which in turn is fed by a coaxial line projected through the vertex and along its axis, and having a quarter wave cylindrical choke positioned on the outer conductor, that the direction of maximum radiation is deflected off from the geometrical axis of the reflector. There is thus produced by a structure, physically at the focus, a radiation beam having electrical offset or squint. This effect has been attributed to the fact that the choke causes standing waves on the outer conductor between the choke and the dipole thus in effect providing another dipole positioned in an axial direction in the neighborhood of the actual dipole and hence perpendicular to the latter. The radiation from the actual dipole and from the virtual one, if in particular phase relation, will combine in such a way that the direction of maximum radiation of the reflected beam will be off the axial direction, the degree of offset depending on the relative phases in the actual dipole and in the axially directed radiator and also on the relative intensity of excitation of the two radiating elements. A more detailed description and suggested explanation of these phenomena may be found in the patent application of Rufus W. Wright, Serial No. 511,863, filed November 26, 1943.

In the invention of Wright the phase relation was not easily adjustable but was intended to be left constant so that the angle of offset from the axis also remained constant. By rotating portions of the system the radiation beam was caused to scan a conical region. The present invention provides a second actual dipole positioned in an axial direction in the region of the focus of the reflector and energizes it separately from the same source which feeds the principal dipole antenna element perpendicular to the axial direction. By use of a variable power dividing device the relative degree of excitation of the respective dipoles may be caused to vary rapidly back and forth so that the degree of offset may be made to vary thus producing a rapid transverse scanning across a narrow angle. Alter-

natively a phase-varying feed may be used and the same result will occur.

It is therefore one object of this invention to construct an antenna system of the paraboloidal reflector type which will provide a radiation beam whose direction of maximum may be caused to scan rapidly over a narrow transverse angle.

It is another object to construct an antenna system having a paraboloidal reflector illuminated by two dipoles near its focus, one positioned perpendicular to the axis of the paraboloid and the other parallel to the axis, and having means for energizing these dipoles from a common source but in variably differing proportions of excitation respectively.

It is another object to construct an antenna system having a paraboloidal reflector illuminated by two dipoles near its focus one being along the axis of said reflector and the other perpendicular to it, and having means for energizing these dipoles from a common source but in different degree of excitation and in variably different phase.

Other objects and features of the invention may be found in the following detailed description taken with the drawing which is for purpose of illustration and is not to be deemed as defining or limiting the scope of the invention.

The figure is a diagrammatic side view of the antenna system showing a paraboloidal reflector, transverse and axial dipoles and a possible type of variable power divider for distributing power to the dipoles.

Referring now to the figure there is indicated a paraboloidal reflector 1 which may be suitably mounted. Extending through the reflector 1 near the vertex 3 are shown two transmission lines 5 and 7 having inner conductors 9 and 11 respectively and outer conductors 13 and 15 respectively. These two coaxial transmission lines 5 and 7 are parallel to the axis 14 of the paraboloid and relatively close to it, the dimensions of the figure being out of true proportion for the sake of clearness.

The two coaxial feed lines 5 and 7 extend forward to the region of the focus 18 of the paraboloidal reflector 1. Line 5 supports and energizes at its end near the focus 18 a dipole 19 perpendicular to the axis 14 i. e. horizontally transverse the face of the reflector 1. Line 7 supports and energizes a dipole with arms 21 and 22 extending in the axial direction parallel to axis 14 and hence perpendicular to the direction of dipole 19, also near the focus 18. Near

55 may be considered to mean as near the focus

as the electrical and mechanical construction of the two lines 5 and 7 and the two dipoles 19 and 21 will permit.

Forward of the transverse dipole 19 substantially a quarter wave length there is positioned a reflector dipole 24 for the purpose of preventing direct forward radiation from the dipole 19 and thereby avoiding an unnecessarily wide beam. This may be supported by an insulating mounting (not shown) or by extending the line 5 so as to form a quarter wave stub (not illustrated) to provide support both for the inner conductor 9 and the reflector dipole 24. In this case the dipole 24 would be secured to the outer conductor 13 while the inner conductor 9 would be supported by a shorting plate closing the end of the quarter wave stub that is adjacent dipole 24. One arm of the dipole 19 would be connected to the outer conductor 13, and the other arm would be connected to the inner conductor 9 and extend through a suitable aperture in the outer conductor 13. The application of Wright above mentioned may be referred to for further details of such a reflector and support.

To divide properly between the transverse dipole 19 and the axial dipole 21, 22 the energy from a coaxial feed line 26 with an inner conductor 21 and an outer conductor 28, a variable power dividing device is needed so that the offsetting effect may be produced. By varying the division of power the degree of offset may be varied and hence a transverse scanning will be produced. The relative lengths of lines 5 and 7 from the power divider are adapted to provide the proper phase difference between the excitation of the respective dipoles so that a beam deviation will result. The amount of deviation is then controlled by the relative intensity excitation of the respective dipoles 19 and 21-22, the transverse dipole 19 however having at all times the much greater share of the energy.

One device for variably dividing the power is shown in the figure, including a section of coaxial transmission line with inner conductor 30 and outer conductor 32 connected to the power input line 26 at a junction designated by numeral 34 and also connected to dipole feed line 5 at point designated by numeral 36 and to dipole feed line 7 at point designated by numeral 38. A complete description of this type of variable power divider may be found in patent application of George L. Ragan entitled "Power Divider Circuit" Serial No. 592,798, filed May 9, 1945, now Patent 2,605,356, issued July 29, 1952. In brief, the apportionment of power by the device results from the fact that adjustably positioned short circuiting plungers 40 and 42 are provided so that there results a short circuited stub in parallel with each of the respective lines 5 and 7 which feed the two dipole antenna elements 19 and 21-22. If the two outputs are matched for one setting of the plungers and if also the plungers are mechanically ganged so that the length of one stub is greater than the other at all times by one quarter of a wave length then the input 28 will be continuously matched for all positions of the plungers. Moreover there results a division of power between the two outputs into lines 5 and 7 respectively proportional to the conductances of the respective stubs, while the reactive components introduced by the stubs will cancel at all positions. A suitable frame or yoke and driving mechanism (not shown) may be attached to tubes 44 and 45 to cause the plungers 40 and 42 to move back and forth and thus produce a peri-

odic variation in the power fed to the dipoles 19 and 21-22 respectively. This in turn will cause the radiation beam from the reflector 1 to swing back and forth transversely at the same rate through a small angle.

Deviation of the beam may also be accomplished by varying the relative phasing between the transverse dipole and the axial dipole by variably inserting dielectric material in the feed line to one of the dipoles or by otherwise periodically varying the electrical length of one of the feed lines in any of several conventional ways (not shown).

What I desire to claim and secure by Letters Patent is:

1. A directional antenna system for transverse scanning over a narrow angle, comprising a paraboloidal reflector, a dipole positioned near the focus of said reflector and substantially perpendicular to the direction of the axis thereof, a dipole positioned near the focus of said reflector and substantially parallel to the axis, means for variably apportioning high frequency electrical energy to the said dipoles, and a reflector dipole disposed in spaced relationship to and occupying a position more remote from said paraboloidal reflector than said first named dipole.

2. A directional antenna system for producing a narrow radiation beam which may be caused to scan back and forth through a narrow angle, comprising a paraboloidal reflector, a dipole positioned near the focus of said reflector and substantially perpendicular to the direction of the axis of said reflector, means for variably energizing said dipole with high frequency electric energy, an auxiliary reflector occupying a position more remote from said paraboloidal reflector than said dipole, a dipole positioned near the focus of said paraboloidal reflector and substantially parallel to the direction of said axis, and means of variably energizing said last-named dipole with a relatively smaller amount of said energy.

3. A directional scanning antenna system comprising, a paraboloidal reflector, a dipole positioned near the focus of said reflector and substantially perpendicular to the direction of the axis of said reflector, means for energizing said dipole with high frequency electrical energy, an auxiliary reflector occupying a position more remote from said paraboloidal reflector than said dipole for reflecting the direct forward radiation of said dipole back toward said paraboloidal reflector, a dipole positioned near the focus of said paraboloidal reflector and substantially parallel to the direction of said axis, and means for energizing said last named dipole with high frequency electrical energy of variable phase relative to the phase of said first mentioned energy.

4. A directional scanning antenna system comprising a paraboloidal reflector, two dipoles positioned near the focus of said reflector one substantially parallel to and one substantially perpendicular to the axis of said reflector, two coaxial transmission lines for energizing said dipoles, an auxiliary section of coaxial transmission line, an input transmission line for energizing said auxiliary line, said auxiliary line section having connections respectively with said two coaxial lines on opposite sides of the connection to said input line, two short circuiting plungers inserted in said auxiliary section beyond said connections respectively such that the distance from one plunger to the one of said connections nearer to it exceeds by one quarter of an elec-

trical wave length the distance from the other plunger to the other of said connections, means for causing said plungers to move in unison so as to vary periodically the said distances by equal amounts, and an auxiliary reflector occupying a position more remote from said paraboloidal reflector than said second named dipole.

5. A directional antenna system comprising a paraboloidal reflector, a first dipole positioned near the focus of said reflector and substantially perpendicular to the axis thereof, a second dipole positioned near the focus of said reflector and substantially parallel to the axis of said reflector, a reflector dipole disposed in spaced relationship to and occupying a position more remote from said paraboloidal reflector than said first dipole and means for supplying high frequency energy to said first and second dipoles.

6. A directional antenna scanning system comprising a paraboloidal reflector, first and second antenna elements disposed substantially at the focus of said reflector, one of said antenna elements being oriented parallel to and the other perpendicular to the axis of said reflector, first and second transmission lines extending through said reflector for respectively energizing said first and second antenna elements, an auxiliary section of transmission line coupling said first and second transmission lines, an input transmission line coupled to said auxiliary line section, a pair of mechanically coupled line terminating elements in said auxiliary line section, and means for oscillating said terminating elements in unison.

7. An antenna having variable directivity comprising, a paraboloidal reflector having a finite focus, first and second closely adjacent feed lines projecting through said reflector near the vertex thereof and terminated substantially at the focus of said reflector, first and second antenna elements supported at the termination of said first

and second feed line, respectively, one of said antenna elements being oriented parallel to and the other perpendicular to the axis of said reflector, and means coupled to said feed lines for variably apportioning high frequency energy to said antenna elements.

8. An antenna having variable directivity comprising, a paraboloidal reflector, first and second radiating dipoles each positioned substantially at the focus of said reflector, one of said dipoles being oriented parallel to and the other perpendicular to the axis of said reflector, separate feed lines for said first and second dipoles, and means coupled to said feed lines for variably apportioning high frequency energy to said dipoles.

9. An antenna having variable directivity comprising, a paraboloidal reflector, first and second radiating dipoles positioned near the focus of said reflector, one of said dipoles being oriented parallel to and the other perpendicular to the axis of said reflector, and means coupled to said dipoles for variably apportioning high frequency energy to said first and second dipoles.

10. An antenna having variable directivity comprising, a paraboloidal reflector, first and second radiating antenna elements positioned near the focus of said reflector, one of said elements being oriented parallel to and the other perpendicular to the axis of said reflector, and means coupled to each of said elements for variably apportioning high frequency energy thereto.
